DRINKING GLASS FROSTER

Weldon G. Duke, 1825 Arrow Highway, Covina, Calif.

Filed Aug. 9, 1961, Ser. No. 66,264

Term of patent 14 years

(Cl. D67—3)

Fig. 1.

Fig. 2.

Fig. 3.

Fig. 4.

FIG. 1 is a top plan view of a drinking glass froster, showing my new design;

FIG. 2 is a side elevational view thereof;

FIG. 3 is an end elevational view thereof; and

FIG. 4 is an end elevational view thereof, similar to FIG. 3, with portions of the end wall cut away, for purpose of illustration.

I claim:

The ornamental design for a drinking glass froster, as shown and described.
